UNITED STATES PATENT OFFICE.

DE WANE B. SMITH, OF UTICA, NEW YORK.

WAGON-BOLSTER SPRING.

SPECIFICATION forming part of Letters Patent No. 393,345, dated November 20, 1888.

Application filed November 10, 1887. Serial No. 254,837. (No model.)

To all whom it may concern.

Be it known that I, DE WANE B. SMITH, of Utica, in the county of Oneida and State of New York, have invented certain new and useful Improvements in Wagon-Bolsters, Saddles, and Torsion-Springs; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention consists in the combination of a bolster, saddles, and torsion-springs arranged as hereinafter set forth and claimed.

Figure 1 represents a perspective view of a bolster, the saddles, the torsion-springs, and the sub-bolster. Fig. 2 represents a perspective view of a bolster, and the torsion-springs, showing the sub-bolster removed. Fig. 3 represents a perspective view of one of the saddles. Fig. 4 is a perspective end view of one of the saddles of modified construction and a section view of the torsion-springs and their connection with the saddle. Fig. 5 represents a similar view to Fig. 4, showing a saddle of a modified construction; and Fig. 6 represents a similar view to Fig. 4 of a still further modified construction. Fig. 7 is a perspective view of a link for connecting the saddles and the springs.

The purpose of my invention is to furnish saddles for ordinary bolsters on wagons, on which torsion-springs are mounted, as herein-after more fully pointed out.

In the drawings, 1, Figs. 1 and 2, represents an ordinary wagon-bolster.

2 2 represent the stakes in the bolster.

3 3 represent torsion-springs formed in two parts or sections, the two parts forming a complete spring. Each section is formed of a single piece of steel rod of the required size, length, and temper. Each section has a loop, 4 4, in the rod. The outer ends of each section are bent at an angle to the loop, as shown at 5 5, the ends turning outward. At the inner end of the loop in each section a depression is formed in the rod forming the spring to allow one of the sides of the loop to fit therein, as shown at 6 6, so that the rods forming the loops

of the two sections are brought on the same horizontal plane, in order to fit the under side of a wagon box or sub-bolster, a', as shown in Fig. 1. The sections of the torsion-springs are held to the under side of the sub-bolster or box and are adjustable therein by engaging clips 7 7, for partially engaging the rod forming the springs, which are provided with perforations for receiving bolts 9 9. The sections of the spring are free to be horizontally adjusted under the clips, when the springs may be lengthened or shortened, and when adjusted the same may be rigidly held by tightening the nuts on the bolts.

I provide at the outer ends of each section of the torsion-spring hooks 10 10, for receiving intermediate links, 11 11, which connect with circular hooks 12 12 on the extension-arms of saddle 13, provided with projecting shoulders 14 14, fitting the opposing edges of the bolster, on which the same is mounted crosswise of the bolster, each saddle being placed in close proximity to stakes 2 2, so that slots 15 15 in each end of the sub-bolster engage the sides of the stakes to secure steadiness and accommodate the vertical reciprocal action of the springs when subjected to strain.

Another feature of my invention consists in providing slots 16 in the circular hooks on the arms of the saddle for receiving and retaining the projecting shoulders 17 17, Fig. 7, in the circular hooks, neck 18 fitting loosely in slots 16 16 in the hooks, the looped end 19, Fig. 7, engaging hooks 10 10 on the ends of the torsion-springs, whereby the saddle may be attached and detached from the spring. This, however, may be accomplished in another way by means of links 11 11, which in some instances may be considered preferable.

The superior advantages arising from the use of my saddles may be attained by the use of inclined slots 20 20, Fig. 6, in the ends of the saddles for receiving the ends of the torsion-springs, which are free to work therein, and the same result may be had by the use of triangular openings or slots 20 20, Fig. 5.

I do not claim to be the inventor of the torsion-springs shown in Fig. 2, as this is old; but my invention consists in the peculiar arrangement of the saddles and the connection of the springs therewith as applied to wagon-bolsters.

What I claim as new, and desire to secure by Letters Patent, is—

1. The combination of a saddle adapted to ride crosswise of a wagon-bolster, having projecting arms extending beyond the opposing edges of the bolster, torsion-springs held to a sub-bolster, and connecting-links adapted to connect the arms of the saddle with the torsion-springs.
- 10 2. The combination, with a wagon-bolster, of the saddle placed crosswise thereof, having downward-projecting shoulders for engaging the opposing edges of the bolster, the arms of the saddle extending beyond the edges of the bolster and at right angles thereto, provided with circular slotted hooks on the ends of the arms, the links having shoulders and neck for engaging the slotted hooks, and the torsion-springs connected with the links, substantially 20 as set forth.
- 15 3. The combination of a sub-bolster having slotted ends adapted to engage and slide between the stakes of a wagon, torsion-springs

secured to the sub-bolster and having the ends thereof adapted to be carried by a saddle crosswise of the wagon-bolster, and a saddle adapted to ride the bolster crosswise, having shouldered projections adapted to engage the opposing sides of the bolster, and having arms projecting beyond the bolster for carrying the end of 25 the springs, substantially as set forth.

4. The combination of the sub-bolster adapted to move between the stakes of a wagon, torsion-springs secured to the sub-bolster, the ends thereof connected with the saddle, and a saddle having shoulders to engage the opposing edges of the bolster, and arms extending beyond the edges of the bolster adapted to engage the ends of the torsion-springs.

In witness whereof I have affixed my signature in presence of two witnesses.

DE WANE B. SMITH.
